UNITED STATES PATENT OFFICE.

ALBERT G. ELVIN, OF SOMERVILLE, NEW JERSEY.

MECHANICAL STOKER.

1,137,471.

Specification of Letters Patent. Patented Apr. 27, 1915.

Application filed September 19, 1914. Serial No. 862,434.

To all whom it may concern:

Be it known that I, ALBERT G. ELVIN, of Somerville, in the county of Somerset and State of New Jersey, have invented a certain 5 new and useful Improvement in Mechanical Stokers, of which improvement the following is a specification.

My present invention relates to appliances for feeding fuel to locomotive and other 10 steam boiler furnaces, of the class or type in which the members which act directly to project the fuel into the furnace are in the form of fuel carrying and throwing shovels, moving about vertical axes, adjacent to a 15 firing opening in the furnace, as generally exemplified in Letters Patent of the United States No. 1,058,356, granted and issued to me under date of April 8, 1913.

The object of my invention is to enable 20 the advantages of a mechanical stoker of the type above stated to be attained in practice by a construction which will embody the further advantages of simplification of mechanism and reduction of the number and 25 cost of the operating members of the appliance.

The improvement claimed is hereinafter fully set forth.

In the accompanying drawings: Figure 1 30 is a view, partly in side elevation and partly in section, of the adjoining portions of a coupled locomotive engine and tender, illustrating an application of my invention; Fig. 2, a rear view, in elevation, of the apparatus; 35 Fig. 3, a plan view of the shovel box and shovel; Fig. 4, a vertical central section through the same; Fig. 5, a view, partly in side elevation and partly in section, of the shovel box, showing the feed chute as delivered into the rear thereof; Fig. 6, a transverse section through the shovel, on the line $\alpha\alpha$ of Fig. 3; Fig. 7, a view, in perspective, of the shovel; Fig. 8, a horizontal section through the gear casing of the shovel 40 box; Fig. 9, a view, in perspective, of a modified form of shovel; and, Fig. 10, a transverse section through the same on the line $\gamma\gamma$ of Fig. 9.

My invention is herein, as in Letters Patent No. 1,058,356 aforesaid, exemplified as applied in connection with a locomotive engine (indicated, as a whole, by B) and a tender (indicated, as a whole, by A) which are coupled together for service, in the or-

dinary manner, by a draw bar, C, my invention being applied for the purpose of mechanically conveying fuel from the coal space, a , of the tender, to the firing opening, b , of the firebox, b , of the locomotive, and intermittently projecting apportioned quantities of the fuel through said opening into the firebox.

In the practice of my invention, I provide, at the front end of the coal space, a , of the tender, a supply hopper, 1, through which the fuel is supplied by gravity to the rear end of a longitudinal casing, 2^a , in which there extends a screw conveyer, 2, mounted in suitable bearings in the casing. The conveyer casing is supported in such manner as to permit of relative movements of the locomotive and tender without disturbance of the operation of the conveyer. Any suitable supporting means, as, for example, those set forth in Patent No. 1,058,356, may be used, and as these do not form part of my present invention, they are not herein described.

The forward end of the shaft of the conveyer, 2, is coupled, by a universal joint, 2^e , 80 to a shaft, 4, journaled in bearings in an elevator casing, 8, which is of quadrangular form and is suitably supported closely adjacent to, throughout its length, and parallel with, the rear head of the firebox, b , of the 85 locomotive, an elevator, comprising a plurality of connected links, 8^a , and buckets, 8^b , being fitted to traverse in said casing. The elevator passes over guide sheaves, 8^c , journaled in the casing, 8, and is actuated by a 90 motor, 5, of any suitable and preferred construction. The shaft, 4, to which the shaft of the screw conveyer, 2, is coupled, is rotated by a chain, 4^b , passing over a sprocket wheel, 4^a , on the shaft, 4, and a similar wheel, 95 8^d , on the shaft, 8^e , of one of the guide sheaves, 8^c , of the elevator.

The fuel which is carried, by the rotation of the screw conveyer, 2, from the tender to the forward end of the conveyer casing, is 100 dropped therefrom into the bottom member of the elevator casing, 8, from which it is elevated by the buckets, 8^b , to the top member thereof, which is downwardly inclined in the direction of the movement of the 105 buckets therein. A vertical feed chute, 8^f , communicates, at its top, with the middle portion of the top member of the elevator

casing, and, at its bottom, with a shovel box, 9, which is fixed to a supporting plate, 9^a, secured to the rear head of the firebox, b. The feed chute is shown in Fig. 4 as leading 5 into the shovel box, adjacent to its front, and in Fig. 5, adjacent to its rear, the difference in location being to suit different forms of shovels, hereinafter described. The forward side of the shovel box is fully 10 open to the firing door opening, b', of the firebox, near the lower side thereof, and, in the instance shown, the supporting plate covers the portion of the opening which is above the shovel box. This extension of 15 the supporting plate is not, however, an essential of the construction, as the closure of the upper portion of the opening may, if desired, be effected by sliding doors in the ordinary manner, as in Patent No. 1,058,356 20 aforesaid.

The fuel which is raised in the elevator casing, drops therefrom, through the feed chute, 8^f, into the shovel box, 9, from which successive portions or charges are projected 25 into the firebox, toward the opposite sides thereof, by a fuel carrying and throwing shovel, indicated, as a whole, by 11, which may, by reason of its capability of similarly performing its function in both directions of its forward or feeding traverse, be descriptively termed a "twin shovel", and is fixed on a vertical shovel shaft, 12, journaled in bearings at the bottom of the shovel box. As clearly shown in Figs. 4, 6, and 7, 30 the twin shovel comprises a hub, 11^b, concentric with the opening for its shaft; a vertical longitudinal rib or blade, 11^c, extending therefrom nearly to its opposite end; and horizontal blades, 11^d, extending outwardly from the bottom of the vertical blade, 11^c, on opposite sides thereof, said vertical blade being preferably bifurcated at its outer end, so as to form two outwardly curved hooks, 11^e. A horizontal cut-off 35 plate, 11^f, is, in one form of the shovel, extended from the top of the hub, 11^b, along the top of the blade, 11^c, and a downwardly tapering conical faced extension, 11^g, is formed on the opposite side of the hub. As 40 shown in Figs. 9 and 10, the extension, 11^g, is dispensed with, and the plate, 11^f, is of full circular form.

Swinging movements, in alternately opposite directions, about the axis of the shovel shaft, 12, are imparted to the twin shovel, 11, by the reciprocating movements of a rack, 15, which is fitted to traverse in a gear casing, 9^b, formed on or fixed to the bottom of the shovel box, 9, said rack meshing with 45 a pinion, 12^a, fixed on the shovel shaft, 12. The rack, 15, is coupled, by a link, 16, to the upper arm of a bell crank or elbow lever, 17, the lower arm of which is, in turn, coupled, by a link, 18, to a crank arm, 19, on the 50 shaft, 8^e, of one of the guide sheaves, 8^c, of

the elevator. Reciprocating movements are thereby imparted to the rack, 15, by the rotation of said shaft.

In the operation of a mechanical stoker embodying my invention, the fuel which is transferred from the coal bin of the tender to the elevator casing on the locomotive, is elevated in said casing and drops therefrom into the feed chute, 8^f. In the construction shown in Fig. 4, in which the feed chute communicates with the shovel box adjacent to the front of the latter, the fuel falls on the top of the cut-off plate, 11^f, of the twin shovel, which, when the shovel is in the rear position, prevents it from dropping into the shovel box. As soon as the shovel swings, in either direction, away from the longitudinal central plane of the shovel box, the plate, 11^f, begins to open the lower end of the feed chute to the shovel box, and the fuel falls thereinto, sliding down the inclined surface of the tapering extension, 11^g, which carries it toward the rear of the shovel box, and also acts, on the return stroke, to lift the remainder of the fuel that has not been deposited therein into the fuel chute, thereby preventing tendency to choke the shovel. The deposited fuel is scooped up by the lower horizontal blade of the shovel on the advancing side of its vertical blade, held thereon by the vertical blade, and projected therefrom into the firebox by the forward swing of the shovel, being scattered by reason of being thrown, by momentum, off the supporting horizontal blade, and a portion of it being thrown, by the hook of the vertical blade, toward one of the rear corners of the firebox. When the shovel reaches its full forward position, the feed chute is completely open to the shovel box, and delivers all the fuel which it receives thereto. As the shovel returns to its rear position, the bottom of the feed chute is closed as above described, and thereafter re-opened by the traverse of the shovel in the opposite direction. When the feed chute opens into the rear portion of the shovel box, as shown in Fig. 5, the fuel is dropped thereinto without restriction, and as the vertical blade of the shovel passes the opening of the feed chute, said blade and the horizontal blade on its advancing side scoop up and carry forward the fuel that has fallen before them. The feed chute remains open, to feed all the fuel the elevator buckets will convey, and on the return of the shovel, it scoops up a charge for delivery by its traverse in the opposite direction. The swinging of the shovel, in either direction, about the vertical axis of the shovel shaft, 12^a, projects the charge of fuel which rests upon one of its horizontal blades, and against its vertical blade, into the firebox, and toward the side thereof farther from the advancing side of its vertical blade. Upon the return 130

of the shovel, another charge of fuel is similarly projected into, and toward the opposite side of, the firebox, by its movement in the opposite direction, to its forward position.

5 I claim as my invention and desire to secure by Letters Patent:

1. In a mechanical stoker, the combination of a fuel receptacle adapted to communicate with a furnace opening, a twin shovel 10 facing in both directions and mounted, at one end, on a vertical shaft to swing horizontally in opposite directions for projecting fuel through the furnace opening, and means for intermittently depositing fuel 15 upon opposite sides of said shovel alternately.

2. In a mechanical stoker, the combination of a fuel receptacle adapted to communicate with a furnace opening, a twin shovel 20 facing in both directions, mechanism for swinging said shovel alternately in opposite directions, horizontally, and means for intermittently depositing fuel upon opposite sides of said shovel alternately.

25 3. In a mechanical stoker, the combination of a fuel receptacle adapted to communicate with a furnace opening, a twin shovel facing in both directions, a vertical shaft for said shovel, mechanism for oscillating 30 said shaft to cause the shovel to swing in opposite directions through said receptacle, and means for intermittently depositing fuel on opposite sides of said shovel alternately.

35 4. In a mechanical stoker, the combination of a fuel receptacle adapted to communicate with a furnace opening, a vertical shaft extending into said receptacle, means for oscillating said shaft, a shovel mounted, 40 at one end, on said shaft, and adapted to deliver fuel through said opening when swinging in either direction, and means for intermittently depositing fuel on opposite sides of said shovel alternately.

45 5. In a mechanical stoker, the combination of a fuel receptacle adapted to communicate with a furnace opening, an oscillatory shovel pivoted in said receptacle and adapted to swing horizontally through said opening, a 50 fuel supply conduit for said receptacle, and means operated by the shovel, for intermittently controlling said fuel supply to opposite sides of said shovel alternately.

6. In a mechanical stoker, the combination 55 of a fuel receptacle adapted to communicate with a furnace opening, a fuel supply conduit for said receptacle, and an oscillatory shovel mounted to swing horizontally in said receptacle and having a plate for opening and closing the fuel supply opening, to deposit fuel upon opposite sides of said shovel alternately.

7. In a mechanical stoker, the combination 60 with a fuel receptacle adapted to communicate with a furnace opening, of an oscillatory shovel pivoted to swing horizontally in opposite directions in said receptacle and having a vertical blade divided at its outer end and curved in opposite directions.

8. In a mechanical stoker, the combination 70 with a fuel receptacle adapted to communicate with a furnace opening, of an oscillatory shovel pivoted to swing horizontally in opposite directions in said receptacle, and comprising a radial vertical blade and horizontal blades extending laterally upon opposite sides at the bottom of the vertical blade.

9. In a mechanical stoker, the combination 80 with a fuel receptacle adapted to communicate with a furnace opening, of a twin shovel having oppositely facing fuel carrying and throwing blades and mounted in said receptacle to swing horizontally, in alternately opposite directions, and to pick up 85 and project fuel through the furnace opening in its forward movements in both directions, and means for intermittently depositing fuel upon opposite sides of said shovel alternately.

10. In a mechanical stoker, the combination 90 with a fuel receptacle adapted to communicate with a furnace opening, of a twin shovel having oppositely facing fuel carrying and throwing blades, power actuated 95 means for horizontally swinging said shovel in alternately opposite directions, and means for intermittently depositing fuel upon opposite sides of said shovel alternately.

11. In a mechanical stoker, the combination 100 with a fuel receptacle adapted to communicate with a furnace opening, of means for intermittently depositing fuel in the receptacle, on opposite sides thereof alternately, a twin shovel having oppositely facing fuel carrying and throwing blades and adapted to swing forwardly and backwardly through the furnace opening, and power actuated means for horizontally swinging said shovel in alternately opposite directions. 110

12. In a mechanical stoker, the combination 115 with a fuel receptacle adapted to communicate with a furnace opening, of a fuel feed chute leading into said receptacle, a twin shovel having oppositely facing fuel conveying and throwing blades, means, carried by said shovel, for controlling the supply of fuel from the feed chute to opposite sides of the shovel alternately, and power actuated means for horizontally swinging the shovel in alternately opposite directions. 120

13. In a mechanical stoker, the combination 125 with a fuel receptacle adapted to communicate with a furnace opening, of a shovel shaft journaled substantially vertically in said receptacle, a twin shovel fixed, at one end, on said shaft and having oppositely facing fuel carrying and throwing blades, means for intermittently depositing fuel on opposite sides of the shovel alternately, a 130

pinion fixed on the shovel shaft, a rack fitted to reciprocate transversely to the shovel shaft and meshing with said pinion, and power actuated means for reciprocating said rack.

14. In a mechanical stoker, the combination of an elevator casing adapted to be supported adjacent to the rear head of a boiler furnace and to surround a firing opening therein, an elevator traversing in said casing, a fuel receptacle adapted to communicate with the firing opening, a feed chute leading from the elevator casing into said receptacle, a twin shovel journaled substantially vertically in said receptacle and having oppositely facing fuel conveying and throwing blades, power actuated means for traversing the elevator in the casing, and means, actuated by the elevator, for horizontally swinging the shovel in alternately opposite directions.

15. In a mechanical stoker, the combination of an elevator casing of quadrangular form, adapted to be supported immediately adjoining the rear head of a boiler furnace and to surround a firing opening therein, an elevator traversing in said casing, a fuel receptacle adapted to communicate with the firing opening, a feed chute leading from the upper member of the elevator casing into said receptacle, a twin shovel journaled substantially vertically in said receptacle and having oppositely facing fuel conveying and throwing blades, power actuated means for traversing the elevator in the casing, and means, actuated by the elevator, for horizontally swinging the shovel in opposite directions.

16. In a mechanical stoker, the combination of a fuel receptacle adapted to communicate with a furnace opening, and a twin shovel mounted to swing horizontally, in opposite directions, in said receptacle, and comprising a shaft hub, a vertical blade ex-

tending longitudinally therefrom and two horizontal blades projecting from opposite sides of the vertical blade, at the bottom thereof.

17. In a mechanical stoker, the combination of a fuel receptacle adapted to communicate with a furnace opening, and a twin shovel mounted to swing horizontally, in opposite directions, in said receptacle, and comprising a shaft hub, a vertical blade extending longitudinally therefrom, two horizontal blades projecting from opposite sides of the vertical blade, at the bottom thereof, and a horizontal cut off plate extending from the top of the hub along the top of the vertical blade.

18. In a mechanical stoker, the combination of a fuel receptacle adapted to communicate with a furnace opening, and a twin shovel mounted to swing horizontally, in opposite directions, in said receptacle, and comprising a shaft hub, a vertical blade extending longitudinally therefrom and bifurcated into outwardly curved hooks at its outer end, and two horizontal blades projecting from opposite sides of the vertical blade, at the bottom thereof.

19. In a mechanical stoker, the combination of a fuel receptacle adapted to communicate with a furnace opening, and a twin shovel mounted to swing horizontally, in opposite directions, in said receptacle and comprising a shaft hub, a vertical blade extending longitudinally therefrom, two horizontal blades projecting from opposite sides of the vertical blade, at the bottom thereof, and a downwardly projecting conical faced extension on the side of the shaft hub farther from the vertical blade.

ALBERT G. ELVIN.
